CLAIM

The ornamental design for a twin loop toe crest, as shown and described.

DESCRIPTION

FIG. 1 is a top left perspective view of the present design for a twin loop toe crest;

FIG. 2 is a left side view of the twin loop toe crest of the design of FIG. 1;

FIG. 3 is a right side view of the twin loop toe crest of the design of FIG. 1;

FIG. 4 is a top view of the twin loop toe crest of the design of FIG. 1;

FIG. 5 is a bottom view of the twin loop toe crest of the design of FIG. 1;

FIG. 6 is a front view of the twin loop toe crest of the design of FIG. 1;

FIG. 7 is a back view of the twin loop toe crest of the design of FIG. 1;

FIG. 8 is a bottom view of the upper portion of the twin loop toe crest of the design of FIG. 1 in a disassembled state, with the bottom surface being provided with a loop material; and, FIG. 9 is a top view of the lower portion of the twin loop toe crest of the design of FIG. 1 in a disassembled state, with spacers on the top surface being provided with a hook material.
